William Edwards. - Letter Patent Dated May 30, 1812.

They who will be referred to in these letters, to contend, making part of the same, containing a description in the words of the said William Edwards, formerly of his Trade Mill or Machine for separating dry sticks.

The Trade Mill is constructed of timber and should be framed in length three feet in width two and a half feet, and half a foot deep. The timber for the said Mill should be three inches in thickness. The planks for the bottom, pine boards six inches wide. This part is called the stock of the mill, the end of which should be placed towards the water wheel, which end should be open to the opposite end, and should be made of timber twelve inches thick, the centre of which should be eight feet from the planks, so placed as to be parallel with the top of the stock. The whole should be firmly ground together. The instant part of the stock towards the end formed by timber is made square so that the sides, when separated, open by the Worms, may receive and hold the cloth doas, when separated open in a fulling mill. The Worms are made square upon the sides are two pieces of timber fifteen inches square and three & a half feet long, square at the end and taken off at the other by a single of four points so that it should be inserted into the worm pieces three quarters of an inch in diameter. These pieces should project three inches. The Worms are made to operate upon the sides by having two holes inserted to them two and a half inches of the square end, these worm holes should be made of a substantial timber in a size of eight inches by three inches and one half inch and one and a half feet in length. The Worms should have the Worms passed through them by a Worm of the size of the Worms & inserted with edges to eight feet from one end, leaving one foot to each other which have inserted in a water wheel, a mortice should be made in the timber running one end of the Worm part and a square and seven feet from the end of the Worm in this

William Edwards, Inventor. Dated Dec³⁰ 1810.
The schedule referred to in these Letters Patent, and making part
of the same, containing a description in the words of the said William
Edwards himself of his improvement in tanning leather.

This improvement consists in the application of heat to the
tanning of said leather this is done either by passing a cylinder
through a vat filled with bark and water so calculated as to
receive wood or other fuel at one end of the cylinder which shall
be inserted into the vat. The other end of the cylinder forming
a right angle should rise above the top of the vat to conduct
the smoke from the fire. Heat may also be applied by steam
by setting a wooden vat upon a boiler connecting them together
and in various other methods the effect is to entirely extract
the tanning principle from the bark in a short time and
with less produce a strong decoction of the bark which applied
to the hide when being upon the board, shortens the process
and produces a strong effect and time in the process.
